CLAIM

The ornamental design for an air humidifier as shown and described.

DESCRIPTIONFIG. 1 is a front view of the air humidifier;
FIG. 2 is a back view thereof.

FIG. 3 is a left side view thereof,

FIG. 4 is a right side view thereof,

FIG. 5 is a top view thereof,

FIG. 6 is a bottom view thereof.

FIG. 7 is a top perspective view; and,

FIG. 8 is a bottom perspective view thereof.

In the drawings, the broken lines depict portions of the air humidifier that form no part of the claimed design.
